UNITED STATES PATENT OFFICE.

WILLIAM H. AIDE, OF DODGEVILLE, WISCONSIN, ASSIGNOR OF ONE-HALF TO ELMER E. JACKSON, OF DODGEVILLE, WISCONSIN.

HARNESS-SADDLE SPRING.

No. 923,102.

Specification of Letters Patent. Patented May 25, 1909.

Application filed September 9, 1908. Serial No. 452,310.

To all whom it may concern:

Be it known that I, WILLIAM H. AIDE, a citizen of the United States, residing at Dodgeville, in the county of Iowa, State of Wisconsin, have invented certain new and useful Improvements in Harness-Saddle Springs; and I do hereby declare the following to be a full, clear, and exact description of the invention, such as will enable others skilled in the art to which it appertains to make and use the same.

The invention relates to harness saddle springs and more particularly to the class of springs adapted to be fixedly connected with-in a saddle and carrying side straps for connection with a belly or girth band of horse harness or the like.

The primary object of the invention is the provision of harness saddle springs mounted within a saddle and carrying side straps adapted to be connected to a belly or girth band of a harness so as to support said band to permit a slight give or yielding qualities between the saddle strap and the said girth or belly band and thereby overcome the binding of the latter about the animal.

Another object of the invention is the provision of a flexible connection between a saddle and side straps of a harness to permit a slight give between the saddle and a belly or girth band connected to the side strap so as to prevent undue frictional rubbing of said band upon the hide of an animal when the saddle is in use.

With these and other objects in view the invention for example consists in the construction and the combination and arrangement of the parts as will be more fully hereinafter described and as illustrated in the accompanying drawings embodying the preferred form of construction of the invention.

It is to be understood that changes, variations and modifications may be made such as come properly within the scope of the claim hereunto appended without departing from the spirit of the same.

In the drawings:—Figure 1 is a side elevation of a harness saddle with the invention applied thereto and the same being partly broken away. Fig. 2 is a top plan view of a harness saddle with the top strap or outer

covering strip of the same removed and the invention in position thereon. Fig. 3 is a detail perspective view of one of the harness saddle springs removed from a saddle.

55

Similar reference characters indicate corresponding parts through the several views of the drawings.

In the drawings:—The numeral 5 designates generally a harness saddle of the ordinary construction, comprising a tree 6 having connected to its under face a back pad 7 and upon the top face is mounted a covering strip 8. Fitted within the saddle 5 at opposite sides thereof between the tree 6 and covering strip 8 are yieldable devices 9 forming the saddle spring comprising U-shaped sections 10 and 11, each having formed at the end of its legs 12 eyes or loops 13 for slidably connecting the sections together. Surrounding the legs 12 of the said sections are coiled expansion springs 14, the opposite ends of which have their bearings against the eyes or loops 13 and are adapted to permit yielding of the sections with respect to each other. The section 10 is formed at its closed end with a loop 15 which receives the threaded shank 16 of a terret 17 mounted upon the pad skirt and which shank securely fastens the yieldable device 80 in position within the saddle between the tree and covering strip thereof.

70

75

Connected to the closed end of the section 11 is a side strap 18, the latter forming a connection for a belly or girth band 19 of a harness and which band is placed about the belly of a horse while the saddle is placed on the back of said horse.

85

It is obvious that the yieldable devices having connection with side straps and mounted within the saddle afford a slight give to the belly or girth band connected to said side straps to effect a comfortable fit of these parts when applied to a horse or the like. Of course, it will be understood that the springs 14 will be of sufficient tension to hold the strap 18 and the belly or girth band in position upon a horse so that they will be prevented from becoming accidentally disarranged about the animal.

100

What is claimed is:—

In combination with a harness saddle and

belly band, of yieldable devices mounted within the saddle, each comprising slidably connected U-shaped members, eyes formed on the ends of said members, expansion springs coiled about the members and having their bearings against said eyes, a loop formed on one of the said members for connection of the same with the saddle, and a

strap carried by the other U-shaped member for connection with the belly band.

In testimony whereof, I affix my signature, in presence of two witnesses.

WILLIAM H. AIDE.
